UNITED STATES PATENT OFFICE.

NICHOLAS RATCHFORD, OF PLAIN CITY, ASSIGNOR OF ONE-HALF TO LEWIS D. EVANS, OF COLUMBUS, AND CHARLES N. BOYD, OF PLAIN CITY, OHIO.

RAILWAY-FROG.

SPECIFICATION forming part of Letters Patent No. 470,009, dated March 1, 1892.

Application filed August 10, 1891. Serial No. 402,241. (No model.)

To all whom it may concern:

Be it known that I, NICHOLAS RATCHFORD, a citizen of the United States, residing at Plain City, in the county of Madison and State of Ohio, have invented a certain new and useful Improvement in Railway-Frogs, of which the following is a specification.

My invention relates to the improvement of railway-frogs of that class wherein the frog rail or tongue is automatically thrown by the weight of a moving train or car, and has particular relation to that construction of railway-frogs shown in former patents, Nos. 433,148, of July 29, 1890, and 434,525 of August 19, 1890, granted to myself and Lewis D. Evans.

The objects of my present invention are to provide improved means for automatically returning or moving the frog-rail or tongue outward from connection with the main track after the passage of a train and at the same time elevate the tongue-operating rail to its normal position, to obviate the necessity of employing springs to accomplish the above objects, and to produce the desired movement of said parts in a simple and reliable manner without unnecessary friction and at a reasonable expense. These objects I accomplish in the manner illustrated in the accompanying drawings, in which—

Figure 1 is a plan view of a portion of a main and side track of a railway, showing the railway-frog and its operating mechanism. Fig. 2 is a sectional view on line $x-x$ of Fig. 1. Fig. 3 is a sectional view on line $y-y$ of Fig. 1; and Fig. 4 is a perspective view of the frog-operating weight and bar.

Similar figures of reference refer to similar parts throughout the several views.

The numeral 1 indicates one of the main-track rails, which, as described in the said former patents, are continuous at the frog-point.

2 represents the outer and 3 the inner side-track rails, which intersect the main-track rails at the usual angle. As described in the said former patents, a suitable supporting-block 4, the upper side of which is flush with the upper side of the main-track rails, is made

to adjoin the outer side of one of said main-track rails at the frog-point or point of intersection of the rails 3 and 1. Upon this supporting-block 4 is supported a frog-rail section or tongue 5, one end of which is pivoted upon one end of said block 4, as indicated at 6. This frog-rail 5 normally lies upon the block 4 in a position parallel with the main-track rails, and has its rear end supported in such position that when moved inward, as hereinafter described, upon its pivot it will be brought into alignment with the sections of the side-track rail 3, which, as described in said former patents, are elevated to the height of said frog-rail.

Supported adjacent to the inner side of the outer side-track rail 2 is an operating-rail 7, in the inner side of which is formed a longitudinal channel 8. This operating-rail, as described in said former patents, is formed in two sections, hinged near the centers of their lengths at 9, the outer ends of said sections being pivotally connected with the side-track rail 2. The upper portion of the channeled operating-rail is normally supported, as hereinafter described, above the outer side-track rail, and the outer end of a bell-crank lever 10 is pivotally connected with a lug 11, which projects from the under side of said channeled rail and which is rigidly connected with the latter. This bell-crank lever is further pivotally connected, as shown at 12, with a lug 13, which projects downwardly from the under side of a bar or plate 14 on the inner side of the operating-rail 7. This bar 14 has its ends supported upon suitable blocks 15, which in turn are supported upon the ties 16, with which said bar is connected. The lower end of the downwardly-extending or vertical arm of the lever 10 is jointedly connected or pivoted at a point between the ties in the slotted end of a lever 17. This lever 17 extends inwardly from its point of connection with the lever 10 in a line parallel with the ties to a point below and on the outer side of the block 4, from which point it is bent upward and thence again inward, and is pivoted, as shown at 18, to a lug 19, which projects outwardly from the outer side of the frog-rail 5, near the rear

pivoted portion of the latter. From the under side of one of the sections of the operating-rail I cause to depend a short bearing-arm 20, in the lower end of which is journaled the 5 crank end of a rod or shaft 21, the horizontal body of which extends outward from its crank portion in the direction of the ties and bearing in suitable boxings or journal-bearings 22, which are formed with or supported upon 10 transverse supporting-bars 23, which extend between and are secured upon two or more ties. On the outer side of the outer one of these bearings this rod or shaft 21 is bent at right angles with the direction of the ties, 15 said bent portion being flattened or squared, and provided at desired intervals with pin perforations, as indicated at 24. This flattened or squared portion 21 is, as shown in the drawings, made to pass loosely through 20 and support at the desired point thereon a suitable weight 25, which is normally supported near the earth, and which, together with the desired portion of the shaft 21, may be suitably covered or housed to prevent the 25 entrance of rain or snow. When the weight 25 is down or in its normal position, the crank end of the shaft 21 is held at such elevation as to result in a corresponding elevation of the central portion of the operating-rail, resulting in the incline of the sections of the latter from their hinge-point toward their outer ends.

The operation of my improved device is as follows: A train which has been switched from 35 the main track onto the side track travels upon the latter until the outer car-wheels come into contact with and run upon the operating-rail. The weight thus imparted to said operating-rail results in a depression of the latter, which, 40 through the connection of the shaft 21 with the arm 20, results in a turning of said shaft within its bearings and a consequent elevation of the weight 25. This downward movement of the operating-rail also serves to depress the upper and shorter arm of the bell-crank 10, and to cause a movement toward the main-track rail of the lower and longer arm of said bell-crank. This movement of 45 the bell-crank results, as will readily be seen, in an inward movement of the lever 17, which, through its connection with the frog-rail 5, results in causing the latter to slide upon its block 4 and the upper side of the rail 1 until the beveled outer end of said frog-rail is 50 in engagement with the side-track rail. As shown in dotted lines in Fig. 1 of the drawings, this movement of the frog-rail results in bringing the latter into alignment with the side-track rail 3 and in the formation thereby 55 of a substantially continuous rail. As will readily be seen, this movement of the frog-rail will be accomplished before the wheels of the car reach the frog-point, and admit of the passage of the inner wheels of said car 60 over the frog-point without contact with the main-track rail, and without the necessity of 65

forming any break whatever in the rail. The cars having passed over the operating-rail, and the latter being thus released from weight or pressure, the weighted portion of the shaft 70 21 will drop to its normal position and the crank end of the shaft will be sufficiently raised to again drive the operating-rail in position for use. This return of the operating-rail to its normal position will result, through 75 the connection therewith of the levers 10 and 17, in a return of the frog-rail to its normal position upon its support and a clearing of the main-track rail.

From the construction and operation described it will be seen that the means employed for transmitting the proper motion to the parts are exceedingly simple and are such as to produce but slight friction of the parts and render the latter durable and flexible. 80 By sliding the weight 25 to different points upon the bar or shaft 21, and inserting suitable pins 27 at each end thereof, through the proper perforations 24, the weight may be adjusted to the desired position upon its supporting-bar.

Having thus fully described my invention, what I claim, and desire to secure by Letters Patent, is—

1. The combination, with the main and side track rails, a movable frog-rail pivotally supported, as described, adjacent to and above the main-track rail, the sectional hinged and pivoted channeled operating-rail adjacent to the inner side of the outer side-track rail, of 95 a bell-crank lever fulcrumed adjacent to said operating-rail and having its shorter arm pivoted to the latter, a lever 17, pivotally connected with the frog-rail 5 and the longer arm of the bell-crank 10, and means for returning 100 the operating-rail to its usual elevated position, substantially as and for the purpose specified.

2. The combination, with the intersecting main and side track rails, the pivoted frog-rail supported, as described, adjacent to and above the main-track rail, a pivoted and jointed channeled operating-rail 7 adjacent to the inner side of the outer side-track rail 2, of a shaft 21, having a crank-shaped inner end, 115 the end of the latter journaled to the under side of the operating-rail, the body of said shaft supported in suitable boxings, as described, a weight upon the outer portion of said shaft, and a pivoted lever connection between the operating-rail and the pivoted frog-rail, by means of which the latter is forced 120 laterally when said operating-rail is depressed, substantially as specified.

3. The combination, with the intersecting 125 main and side track rails, the pivoted frog-rail supported, as above described, adjacent to and above the main-track rail, pivoted and jointed channeled operating-rail 7 adjacent to the inner side of the outer side-track rail 2, 130 bell-crank 10 fulcrumed adjacent to the operating-rail, its upper and shorter arm pivot-

ally connected with the latter, a lever 17, having its ends pivotally connected, respectively, with the longer arm of the bell-crank 10 and the frog-rail 5, of a shaft 21, having a crank-shaped inner end, the end of the latter journaled to the under side of the operating-rail, the body of said shaft supported in suitable

boxings, as described, and a weight upon the outer portion of said shaft, substantially as and for the purpose specified.

NICHOLAS RATCHFORD.

In presence of—

HOWARD C. BLACK,
E. H. REEL.
